His Attorney

UNITED STATES PATENT OFFICE.

JOHN K. UNDERWOOD, OF GENEVA, NEW YORK, ASSIGNOR TO THE AMERICAN OPTICAL COMPANY, OF SOUTHBRIDGE, MASSACHUSETTS.

FRAME FOR SIGHT-TESTING SPECTACLES.

SPECIFICATION forming part of Letters Patent No. 430,763, dated June 24, 1890.

Application filed February 19, 1890. Serial No. 341,240. (No model.)

To all whom it may concern:

Be it known that I, JOHN K. UNDERWOOD, of Geneva, county of Ontario, State of New York, a citizen of the United States, have invented certain new and useful Improvements in Frames for Sight-Testing Spectacles, of which the following is a full, clear, and exact description, reference being had to the accompanying drawings, forming part of this specification, in which—

Figure 1 is a front elevation of a sight-testing spectacle-frame containing my invention. Fig. 2 is a rear elevation of the same. Fig. 3 is a top view or plan of the same. Fig. 4 is a vertical section on the line $x-x$, Fig. 1. Fig. 5 is a similar section on the line $y-y$, Fig. 2. Fig. 5^a is an enlarged section of the upper portion of Fig. 5, and Fig. 6 is a plan of the nose-piece detached.

My invention consists in the devices hereinafter described, whereby the lens-holding frames are adjustably mounted on their supporting-bar, and whereby the nose-piece is given adjustability, and as more particularly recited in the claims.

A is the main bar of the frame upon which the various working parts are mounted.

B are the lens-holding frames, which may be in any of the well-known forms, and which are mounted on the bar A so as to be adjustable toward and from each other thereon.

C is the arm carrying the nose-piece, and arranged on the bar A midway between the lens-frames, and having adjustability vertically on the bar by means of a bridge a on the bar, under which the arm C passes, and a set-screw a' in said bridge working on the arm, whereby the arm is held rigidly in its desired position.

For the purposes of my invention any other known means for giving vertical adjustability to the arm C on the bar may be employed.

A feature of my invention consists in the bar A when formed or provided with a recess a^2 on its rearward side extending longitudinally from end to end of the bar, as shown, and adapted to receive and inclose the screw-rod D, which actuates the lens-frames B. The bar A may be given any desired form or outline in cross-section; but I prefer to form it

of two plates or strips of suitable metal which meet at a right angle, and one of which strips, as a^3 , forms the top face of the bar, while the other constitutes the front face a^4 , as shown. Within the recess thus constituted on the 55 rearward side of the bar by this said inverted-L-shaped metal strip I locate the screw-rod D, and I attach the lens-frames B to their respective reverse threads $d-d'$ on the rod D by means of nuts d^2 , which play on said threads 60 and which are united to clips d^3 , a lip d^4 of which engages and rides the upper face a^3 of the bar A. The clips are fixed on the lens-frames, as shown, and a flange b on said frames engages and traverses the front face a^4 of the 65 bar A. The clips d^3 are preferably formed of spring metal, and the lens-frames are held to proper position on the bar A by the lip d^4 on each clip and the flanges b on the lens-frames. The rod D has the customary thumb- 70 pieces d^5 at its ends beyond the bar A, by which the rod may be turned to adjust the lens-frames on the bar. The lips d^4 may serve in the nature of pointers to traverse a scale marked on the upper face of the bar, as shown 75 in Fig. 3.

E is my improved nose-piece, and this feature of my invention consists in a bar e, carrying upon its rearward end the nose-bridge e' , and passing horizontally through a sleeve 80 e^2 , fixed on the lower end of the vertically-adjustable arm C. A set-screw e^3 works transversely in the sleeve e^2 to hold the bar e in its adjusted position in the sleeve. The bar e may have an index-scale on its upper face, 85 as shown in Fig. 6, and an end of the sleeve may serve in connection with this scale to indicate the distance of the nose-bridge e' from the plane of the lenses when the testing-frames are placed on the face of an individual. 90

What I claim as my invention, and desire to secure by Letters Patent, is—

1. In a frame for sight-testing spectacles, the combination of a bar A, recessed longitudinally at a^2 on its rearward face, the screw-rod D, located in said recess, the lens-frames B, having the flanges b , engaging the front face of said bar, and the clips d^3 , fixed on said lens-frames and having a lip d^4 , engaging the upper face of said bar, together with nuts d^2 , 95 100

carried by said clips and working on said screw-rod, substantially as set forth.

2. In a frame for sight-testing spectacles, the combination, with the lens-frames B and 5 their adjusting-screw rod D, of the bar A, composed of the plates a^3 and a^4 , constituting, respectively, the top and front faces of said bar and meeting at substantially a right angle, said screw-rod being behind the front and 10 beneath the top plate, and a flange on each lens-frame engaging the front plate of the bar, substantially as and for the purpose set forth.

3. In a frame for sight-testing spectacles, the combination, with the arm C, having vertical adjustment on the bar A, carrying the 15 lens-frames B, of the sleeve e^2 on said arm, and the bar e , seated horizontally and longitudinally adjustable in said sleeve and carrying the nose-bridge e' on its rearward end, substantially as set forth.

JOHN K. UNDERWOOD.
